UNITED STATES PATENT OFFICE.

GEORGE E. COUTANT, OF DECATUR, ILLINOIS.

END MOUNT FOR CAR BUFFERS.

Application filed May 15, 1925. Serial No. 30,479.

This invention relates to improvements in end mounts for car buffers and has for its object to provide a construction of that character which will give extended bearing surface while permitting the use of a compact arrangement and the necessary movement for the buffer spring end.

This and other objects will be more fully set forth and described in the following specification and shown in the accompanying drawings, in which:

Fig. 1 is a plan view of the upper buffer of a railway car with associated car structure.

Fig. 2 is a vertical section along the line 2—2 of Fig. 1, drawn to an enlarged scale.

Fig. 3 is a horizontal section along the line 3—3 of Fig. 2.

Fig. 4 is a view similar to Fig. 3 showing the link at its extremities of travel.

Fig. 5 is a plan view of a modified form of end construction.

Fig. 6 is a vertical section drawn to an enlarged scale along the line 6—6 of Fig. 5.

Fig. 7 is a horizontal section along the line 7—7 of Fig. 6 showing the spring end at one limit of travel.

Fig. 8 is a view similar to 7 showing the spring end at the opposite limit of travel.

Like numerals refer to like elements in the drawings, in which 10 designates an end portion of a railway upper car frame. 11 is a portion of the end plate (see Figs. 2 and 6) to which the buffer spring 12 is operatively attached, the spring 12 being of well-known laminated construction including a main full-length leaf 12^a, the ends of which are bent or grooved at 12^b to engage a pivot-pin 13. The pivot-pins are carried by end links 14, which are provided with a pair of spaced parallel plate members 14^a. Each pin 13 is located near one end of the plates 14^a, which are enlarged toward and at their other ends through which extend the arms 15^a of U-bolt 15. A split or cotter-pin 16 through one of the protruding ends of the U-bolt 15 maintains the same against accidental removal.

At each end of the spring 12 is mounted a bracket 18, which is secured by rivets 19 or the like to the car end, as shown in Figs. 1 and 2, for example. Each of these brackets is provided with the stop-flanges 18^a at each side (see Fig. 3) and the spaced top and bottom plates 18^b provided with a plurality of apertures 18^c to permit in-

sertion therethrough of the arms of U-bolt 15, the bottom plate also having an aperture 18^d to permit egress of dirt, water or the like. Each of the plates 14^a of the link 14 is provided with the heart-shaped opening 14^e into which extends the flange 14^d, thus forming a pair of seats or contact surfaces 14^e (see Figs. 3 and 4), which partially embrace the arms 15^a of the U-bolt 15, when in normal position. At its center, the spring 12 is provided with an engaging band 20, which is pivotally attached to a bracket 21, carried by a diaphragm face plate 22, between which and the car end extends a diaphragm 23 in well-known manner. Under buffing strain, the face plate 22 is moved against the action of spring 12, toward the car end, and to accommodate compressive movement of the spring 12, the links 14 are moved outwardly as shown in Fig. 4, until the ends of plates 14 strike the stop-flanges 18^a. During this movement, the link 14 is journaled upon one of the U-bolt arms 15^a, the aperture 14^e permitting the movement as illustrated. When the spring moves outwardly from normal position, the links 14 will assume the position indicated in dotted lines in Fig. 4, and will be journaled upon the other U-bolt arm 15^a. In this manner, and by this construction, rotation of the thrust-receiving member 15, is prevented, and an increased bearing surface is provided for the journaling of the end links 14 by providing spaced members or surfaces, one of which assumes the journaling of the link for movement from normal position in one direction, and the other similarly, for movement from normal in the opposite direction. The parts may be readily removed and reassembled or replaced without the necessity of removing the fixed brackets.

In Figs. 5 to 8, I have illustrated a modified form of my invention, in which in lieu of the U-bolt 15, I provide a flat, wide bar 25, extending through suitable apertures in the bracket plates 18^b, this bar being overturned or bent at its upper end at 25^a and provided with an aperture for the insertion of a cotter-pin 26 at its lower protruding end.

In this form of construction, links 27 carry the pivot-pins 13 at their smaller ends and are provided with apertures 27^c one end of each of which is flattened at 27^a to rest against the flat surface of the bar 25 when in normal position.

At the other end of the flat surface 27^a is a curved contact surface 27^b conforming to the rounded sides 25^b of the pin 25. With this form of construction, under buffing actuation and compression of the spring 12, the links 27 will be moved or rocked to position shown in Fig. 7, during which movement a rounded end of the pin 25 receives the thrust from the corresponding rounded contact surface 27^b of the link 27. On movement from normal in the opposite direction, the link 27 will move to the position shown in Fig. 8, and thrust and bearing contact will be at the opposite side of the pin 25 and the corresponding rounded surface 27^b of the link. In this manner, thrust and bearing is distributed between two surfaces of the pin.

It will be apparent that by the construction described above, not only will greater bearing surface be provided but the center of rotation of the link will be shifted for the movement in different directions from normal position, this shift being away from the direction of movement of the link, thereby permitting a greater rotation within the limited confines of the supporting bracket.

It will be apparent that my invention is susceptible of modification and I do not wish to be restricted to the forms shown and described, except as defined in the appended claims.

What I claim is:—

1. In combination, a bracket, a buffer spring, a link pivotally connected to one end thereof, pivot means carried by said bracket and comprising a pair of spaced bearing surfaces, said link being provided with a pair of spaced portions corresponding to and contactable with said bearing surfaces, one of said portions being journaled on a corresponding bearing surface when said link is moved from normal position in one direction and the other portion being journaled on the other bearing surface when said link is moved from normal position in the other direction.

2. In combination, a bracket, a buffer spring, a link pivotally connected to one end thereof, pivot means carried by said bracket comprising a pair of spaced bearing surfaces, said link being provided with spaced portions corresponding to and contactable with said bearing surfaces whereby upon movement of said link from normal position in one direction, one of said portions will be journaled upon the corresponding bearing surface, and upon movement in the op-

posite direction from normal, the other of said portions will be journaled upon the other of said surfaces, said link comprising spaced top and bottom portions apertured to permit said movement without interference from said pivot means.

3. In combination, a bracket comprising top and bottom plates, a pivot member extending between said plates and provided with spaced bearing surfaces, an end link mounted upon said pivot member and having portions constructed and arranged to bear upon said bearing surfaces of said pivot member.

4. In combination, a bracket comprising top and bottom plates, a pivot member extending between said plates and provided with spaced bearing surfaces, an end link mounted upon said pivot member and having portions constructed and arranged to bear upon said bearing surfaces of said pivot member, said link being provided with a through aperture surrounding said pivot member and permitting movement of said link relative thereto.

5. In combination, a bracket, a link, a spring having one end pivotally attached to said link, a pair of spaced pivot members carried by said bracket, said link being provided with bearing surfaces normally contacting with said pivot members.

6. In combination, a bracket, a link, a spring having one end pivotally attached to said link, a pair of spaced pivot members carried by said bracket, said link being provided with bearing surfaces normally contacting with said pivot members and constructed and arranged in such wise that one of said portions will be moved out of contact with the corresponding pivot member upon movement of said link from normal position in one direction and the other upon movement of said link from normal position in the other direction.

7. In combination, a bracket, a buffer spring, a link pivotally attached to one end thereof, pivot means carried by said bracket provided with a pair of spaced bearing surfaces, said link being provided with bearing portions contactable therewith, the bearing contact between said link and pivot means being shifted laterally in a direction opposite to the direction of travel from normal position of said pivoted spring end.

In witness whereof, I hereunto subscribe my name to this specification.

GEORGE E. COUTANT.
